UNITED STATES PATENT OFFICE

168,427

WELDING ROD HOLDER

Jack L. Simpson, Jacksonville, Fla.

Application August 7, 1952, Serial No. 20,940

Term of patent 3½ years

(Cl. D26—1)

To all whom it may concern:

Be it known that I, Jack L. Simpson, a citizen of the United States, residing at Jacksonville, in the county of Duval, and State of Florida, have invented a new, original, and ornamental Design for a Welding Rod Holder, of which the following is a specification, reference being had to the accompanying drawing, forming part thereof.

Figure 1 is a side elevational view of a welding rod holder, showing my new design;

Figure 2 is a top plan view thereof;

Figure 3 is a rear end view, and

Figure 4 is a front end view of the same.

I claim:

The ornamental design for a welding rod holder, as shown.

JACK L. SIMPSON.
